(57) **CLAIM**

I claim the ornamental design for a two-sided pan, as shown and described.

DESCRIPTION

This Non-Provisional Design Patent Application is related to U.S. Design patent application Ser. No. 29/791,750 filed contemporaneously herewith on Feb. 4, 2022, entitled “Bakeware Set,” the entire contents of which is hereby incorporated herein by reference.

FIG. 1 is a front, left, top perspective view of a two-sided pan, showing my new design;

FIG. 2 is a left elevation view thereof, the right elevation view being a mirror image thereof;

FIG. 3 is a front elevation view thereof, the rear elevation view being a mirror image thereof;

FIG. 4 is a top plan view thereof;

FIG. 5 is a bottom plan view thereof; and,

FIG. 6 is a bottom, front, left perspective view thereof.
